UNITED STATES PATENT OFFICE.

WILLIAM J. HEPPELLE, OF BLOOMFIELD, NEW JERSEY, ASSIGNOR TO THE STANDARD CARRIER COMPANY, OF NEW YORK, N. Y., A CORPORATION OF CONNECTICUT.

CARRIER-DISTRIBUTING DEVICE FOR PNEUMATIC-DISPATCH TUBES.

Application filed May 21, 1921. Serial No. 471,312.

To all whom it may concern:

Be it known that I, WILLIAM J. HEPPELLE, a citizen of the United States, residing at Bloomfield, in the county of Essex and State of New Jersey, have invented certain new and useful Improvements in Carrier-Distributing Devices for Pneumatic Dispatch Tubes, of which the following is a specification.

10 This invention relates to carrier distributing devices for pneumatic dispatch systems.

The principal object of the invention is to provide carrier distributing means at the central station terminal of a pneumatic dispatch tube which will prevent an excessive accumulation of carriers at an operator's station by automatically diverting more than a predetermined accumulation to a reserve operator's station.

20 The invention takes the form of a movably mounted receiving receptacle normally arranged so that arriving carriers are received in a compartment convenient to an adjacent operator's station, but subject to such conditions of balance that the weight of a predetermined maximum number of carriers in the compartment will cause the receptacle to move into a position that will deflect arriving carriers for delivery at a different station. On the other hand the removal of carriers from the receiving compartment again unbalances the device and causes it to move into normal position to again receive carriers in the receiving compartment.

In the drawing.

Figure 1 is a view in side elevation of a device embodying a preferred form of the invention and showing the device in its normal operating position.

Figure 2 is a view similar to Figure 1 showing the device in another operating position.

Referring to the drawing the delivery end 45 1 of a pneumatic dispatch tube is arranged to discharge carriers 2 descending therethrough into a receptacle or compartment 3 formed on one side of a pivotally mounted carrier distributing device 4. The distributing device 4 presents a triangular formation in side elevation with the apex thereof located a short distance below the exit end of the pneumatic tube 1. The point 5 about which the distributing device 4 is capable of rocking is in vertical alinement with the

right-hand edge of the dispatch tube 1 as will be clear.

The normal position of the distributing device 4 is that shown in Figure 1 of the drawing in which the apex 6 of the distributing member is positioned to the right of the path of travel of the carriers 2 as they emerge from the exit end of the tube 1. The left-hand face of the distributing device 4 takes the form of a chute which acts to direct the descending carriers into the compartment 3 at the base of the chute which has already been referred to. In order to hold the distributing device 4 in a position to receive carriers in the compartment 3 a weight member 7 is provided and is located for convenience under the lowermost right-hand extremity of the distributing device 4. The action of the weight member 7 tends to hold the distributing device 4 in its upright position with the left-hand chute of the distributing member in position to receive the carriers and direct them into the compartment 3 as will be clear.

Should carriers be delivered into the compartment 3 at a faster rate than the operator can remove and take care of them then increasing weight provided by the accumulating carriers in the compartment 3 will overbalance the distributing device 4 and raise the weighted end thereof so that the apex 6 of the device is swung to the left in the position indicated in Figure 2 of the drawing. In this position of the distributing member it will be seen that the carriers 2 as they emerge from the dispatch tube 1 engage a chute formed on the right-hand sloping surface of the distributing member 4 which directs them outwardly to the right onto a traveling belt or other receiving means 8 which operates to convey the carriers so diverted to another or reserve operator, thereby relieving the operator in charge of carriers in the compartment 3 and permitting the number of carriers in that compartment to be again reduced to a normal number which can be handled by the operator at that station. It will be clear that instead of variable weight members adjustable springs could be used for normally holding the distributing device 4 in its upright position.

It will be seen that by the use of the device thus described means are provided for

2
automatically preventing the accumulation of an undesirable number of carriers at a given station and giving the operator in charge of the station an opportunity to perform her duties without being unduly hurried in the performance of her work. This relief is given by diverting carriers beyond a given predetermined number from the receptacle 3 in which they are normally received to suitable conveying means which acts to remove and deliver the carriers so received at another station. It will be clear that the number of carriers in the receptacle 3 which may be necessary to tilt the distributing member to diverting position may be varied by means of the use of weight members 7 of different masses or weights.

Preferably the distributing member 4 is mounted on a suitable base 9 which may conveniently form part of the desk or table at which the operators work.

What I claim is:

1. In a carrier distributing device for pneumatic dispatch tubes, a member having a compartment for receiving carriers delivered by a dispatch tube, and means responsive to a predetermined weight in said compartment to deflect arriving carriers away from said compartment.
2. In a carrier distributing device for pneumatic dispatch tubes, a movable receiving member having a compartment for receiving carriers delivered by the dispatch tube, said member being movable under a predetermined weight in said compartment to deflect arriving carriers away from said compartment.
3. A carrier distributing device for pneumatic dispatch tubes comprising: a carrier receiving receptacle having a vertically extending directing member mounted beneath the delivery end of the tube, said directing member being pivotally mounted so as to be tilted from one side to the other of the exit end of the tube, means for normally holding the directing member in position to direct carriers into the receptacle, and said receptacle and directing member being so related that a predetermined carrier weight in said receptacle will tilt the directing

member to a position to divert arriving carriers from the receptacle.

4. A carrier distributing device for pneumatic dispatch tubes comprising a pivotally mounted carrier receiving receptacle, an upwardly extending directing member carried by said receptacle and having its opposite sides forming carrier directing chutes, one of which leads into said receptacle, and means for normally holding said receptacle in position for the directing member to direct arriving carriers into said receptacle, a predetermined weight of carriers in said receptacle acting to overcome said holding means and tilt the receptacle so that the directing member receives carriers in the chute formed on its other face and diverts the carriers away from said receptacle.

5. A carrier distributing device for pneumatic dispatch tubes comprising a pivotally mounted carrier receiving receptacle, an upwardly extending directing member carried by said receptacle and having its opposite sides forming carrier directing chutes one of which directs carriers into said receptacle, a weight member for normally holding said receptacle in position for the directing member to direct arriving carriers into said receptacle, a predetermined weight of carriers in said receptacle acting to overcome the influence of said weight and to tilt the receptacle so that the directing member receives carriers in the chute formed on its other face.

6. In a carrier distributing device for pneumatic dispatch tubes, means for automatically diverting arriving carriers to another station when a predetermined number of carriers has accumulated at a given station.

7. In a carrier distributing device for pneumatic dispatch tubes, a carrier-receiving receptacle, a carrier-directing device normally positioned to direct carriers into said receptacle, said carrier-directing device being constructed and arranged to have its position changed by a predetermined weight of carriers in said receptacle whereby no further carrier will be received in said receptacle until the weight therein has been reduced.

WILLIAM J. HEPPERLE.
